(57) **ABSTRACT**

A lace-like structure of a hive-shaped Venetian blind comprises a blind body made up of a plurality of wave-like arc slats paired up into oval-shaped blind units in cross section. Each wave-like arc slat has a pair of extended flanges disposed at the front and rear sides thereof. Rollers with lace-producing convex edges disposed thereon are adapted to clamp tight the extended flanges thereof and synchronically seal up the pair-up wave-like arc slats via ultrasonic welding art with lace-like patterns cut at the extended flanges thereon via the lace-producing convex edges thereof. Thus, via the lace-producing rollers, the blind body thereof are automatically and synchronically assembled in ready and speedy manner to provide a Venetian blind with lace-like patterns disposed at the front and rear sides thereof in beautiful display.

FIG. 1
PRIOR ART

FIG. 2

FIG. 3

FIG. 4

1

LACE-LIKE STRUCTURE OF A HIVE-SHAPED VENETIAN BLIND

BACKGROUND OF THE INVENTION

The present invention is related to a lace-like structure of a hive-shaped Venetian blind, comprising a blind body made up of a plurality of wave-like arc slats paired up into oval-shaped blind units in cross section. Each wave-like arc slat includes a pair of extended flanges disposed at the front and rear sides thereof. Rollers with lace-producing convex edges disposed thereon are adapted to clamp tight the extended flanges thereof and synchronically seal up the pair-up wave-like arc slats via ultrasonic welding art with lace-like patterns cut at the extended flanges thereon via the lace-producing convex edges thereof. Thus, the blind body thereof is easily and readily assembled to provide a Venetian blind with lace-like patterns disposed at the front and rear sides thereof in beautiful display.

Please refer to FIG. 1. A conventional hive-shaped Venetian blind comprises a blind body 10 attached to an upper and a lower beam 11, 12 there-between. The blind body 10 is made up of a plurality of equal spaced and hive-shaped blind units 13 wherein each hive-shaped blind unit 13 is attached to the others via a fixing plate 14. The blind body 10 thereof is gathered up or unfolded via a pull cord 15.

There are some drawbacks to such conventional hive-shaped Venetian blind. First, the blind body 10 is made up of the hive-shaped blind units 13 individually bound together via fixing plates 14, which is not only troublesome and time-consuming in assembly, and also uncompetitive in the market. Second, the blind body 10 is made up of the simple hive-shaped blind units 13, which is rather plain in decoration.

SUMMARY OF THE PRESENT INVENTION

It is, therefore, the primary purpose of the present invention to provide a lace-like structure of a hive-shaped Venetian blind, comprising a blind body made up of a plurality of wave-like arc slats paired up into oval-shaped blind units in cross section. Each wave-like arc slat has a pair of extending flanges disposed at the front and rear sides thereof. Rollers with lace-producing convex edges disposed thereon are adapted to clamp tight the extended flanges thereof and synchronically seal up the pair-up wave-like arc slats to form the blind body thereof in a ready and speedy manner, facilitating the massive production of the Venetian blind thereof.

It is, therefore, the secondary purpose of the present invention to provide a lace-like structure of a hive-shaped Venetian blind wherein the extended flanges of the paired-up wave-like arc slats, clamped by the rollers, are synchronically sealed up via ultrasonic welding art with lace-like patterns cut thereon via the lace-producing convex edges of the rollers to increase the overall beauty of the blind body thereof in display.

BRIEF DESCRIPTION OF THE DRAWINGS

FIG. 1 is a cross sectional view of a conventional hive-shaped Venetian blind.

2

FIG. 2 is a diagram showing the present invention processed by rollers.

FIG. 3 is a diagram showing the present invention cut with lace-like patterns thereon.

FIG. 4 is a perspective view of the present invention.

DETAILED DESCRIPTION OF THE PREFERRED EMBODIMENTS

Please refer to FIGS. 2, 3. The present invention is related to a lace-like structure of a hive-shaped Venetian blind, comprising a plurality of oval-shaped blind units 21 each made up of two wave-like arc slats 22 correspondingly combined face to face. Each of the wave-like arc slats 22 has a pair of extended flanges 221 disposed at the front and rear sides thereof. Rollers 30 with lace-producing convex edges 31 disposed thereon are adapted to clamp tight the extended flanges 221 thereof and synchronically seal up the paired-up wave-like arc slats 22 thereof via ultrasonic welding art to form oval-shaped blind units 21 as shown in FIG. 2. Meanwhile, the lace-producing convex edges 31 of the rollers 30 will cut through the extended flanges 221 thereof to produce lace-like patterns 221' at both front and rear sides of the oval-shaped blind units 21 thereof as shown in FIG. 3.

Please refer to FIG. 4. The oval-shaped blind units 21, made up of the paired-up wave-like arc slats 22 with lace-like patterns 221' cut at the extended flanges 22 thereon, are assembled to form a blind body 20 of the Venetian blind in a ready and speedy manner. Thus, via the lace-producing rollers 30, the paired-up wave-like arc slats 22 are synchronically and automatically assembled with ease and speed, facilitating the massive production of the blind body 20 thereof. Besides, the lace-like patterns 221' cut by the lace-producing convex edges 31 of the rollers 30 thereof also increase the overall beauty of the blind body 20 thereof in display.

What is claimed is:

1. A hive-shaped blind structure comprising:

a plurality of blind units, each of the plurality of blind units having two slats, each of the two slats having:

a) a curved cross section; and
b) two extended flanges, each of the two extended flanges has a curved pattern cut along a length of an external edge thereof, the two extended flanges of a first slat of the two slats are connected to the two extended flanges of a second slat of the two slats with a hollow interior formed therebetween,

wherein two adjacent blind units of the plurality of blind units are connected to a center of each of the plurality of blind units, the center is located between the curved pattern of each of the two extended flanges.

2. The hive-shaped blind structure according to claim 1, wherein the two extended flanges of the first slat are connected to the two extended flanges of the second slat by ultrasonic welding.
